UNITED STATES PATENT OFFICE.

WILLIAM P. HORN, OF MOUNT VERNON, NEW YORK, ASSIGNOR TO INTER-OCEAN
RADIO CORPORATION, OF JERSEY CITY, NEW JERSEY, A CORPORATION OF NEW
JERSEY.

DESIGN FOR A RADIO LOUD-SPEAKER STAND.

Application filed May 29, 1925. Serial No. 13,606. Term of patent 7 years.

To all whom it may concern:

Be it known that I, WILLIAM P. HORN, a citizen of the United States of America, residing at Mount Vernon, county of Westchester, and State of New York, have invented a new, original, and ornamental Design for Radio Loud-Speaker Stand, of which the following is a specification, reference being had to the accompanying drawing, forming a part thereof.

Fig. 1 is a front view of a radio loud speaker stand illustrating my new design.

Fig. 2 is a side view thereof.

Fig. 3 is a top plan view thereof.

I claim:

The ornamental design for a radio loud speaker stand, substantially as shown.

WILLIAM P. HORN.
